UNITED STATES PATENT OFFICE.

WILLIAM L. BLISS, OF MILWAUKEE, WISCONSIN, ASSIGNOR, BY MESNE ASSIGNMENTS,
TO CENTRAL TRUST COMPANY OF NEW YORK, A CORPORATION OF NEW YORK,
TRUSTEE.

CARBON BRUSH AND PIGTAIL.

1,112,191.

Specification of Letters Patent. Patented Sept. 29, 1914.

Application filed May 2, 1910. Serial No. 559,013.

To all whom it may concern:

Be it known that I, WILLIAM L. BLISS, a citizen of the United States, residing at Milwaukee, in the county of Milwaukee and State of Wisconsin, have invented new and useful Improvements in Carbon Brushes and Pigtails, of which the following is a full, clear, concise, and exact description, reference being had to the accompanying drawing, forming a part of this specification.

My invention relates to what is known as pig tails for carbon brushes.

One of the objects of the invention is to provide a practical, simple and inexpensive means of securing a lead or other connection to a block of carbon, securing at the same time, good electrical contact and mechanical strength.

The embodiment which I have worked out in practice and which illustrates simply one of many ways of carrying out my invention, is shown in the accompanying drawings, in which,

Figure 1 is a perspective view of the completely assembled article. Fig. 2 is a side elevation of the carbon block. Fig. 3 is a vertical section thereof. Fig. 4 is a detailed view.

The block of carbon 1, may be of any suitable form, and is illustrated as being adapted for use as a dynamo or motor brush. The block has a reduced upper end portion 2, over which fits a metallic cap 3, of any good conducting material such as brass or copper, the external surface of the cap and of the block being flush with each other as in Fig. 1. The metallic cap is secured to the block by means of rivets 4 passing through the holes 5 in the block, which rivets are shown in Fig. 4 as having recessed end portions 6, before they are inserted into the block, while after insertion, the slightly projecting ends are spun over to firmly project the cap 3 upon the block 1. The block has two holes 7, extending from the upper surface, as shown in Figs. 2 and 3, and adapted to receive loosely the screws 8, adapted to engage the screw-threaded hole 9 in each rivet 4. When the parts are completely assembled as in Fig. 1, the screws 8 engage a conducting member 10, made by doubling over a strip of metal, preferably of copper or brass, and then bending up one end of the doubled over portion as

clearly shown in this figure, although I do not limit myself to this construction. The end of the bent up portion is adapted to receive the end of a conductor 11, the bared end of which is soldered in the eyelet 12, or otherwise secured in good electrical contact.

From the above it will be apparent that the carbon is subjected to compression stresses only, and furthermore, that good metallic contact with the carbon block is secured, first, by the rivets which hold the sides of the reinforcing piece firmly against the sides of the brush; second, by the screws drawing the rivets against the top sides of the holes of the carbon block; third, by the screws pressing the reinforcing piece down against the top of the brush. It should be further noted that the carbon block may be copper plated if desired, before the cap is applied, in order to secure even better contact.

The invention is not limited to the details of construction shown and described, but includes broadly any equivalent means for accomplishing the same desirable results and coming within the scope of the appended claims.

What I claim as my invention and desire to secure by Letters Patent of the United States is:—

1. The combination with a carbon brush, of a reinforcing conducting member having depending portions engaging certain faces of said carbon brush, a rivet passing through said brush and depending portions for holding said members in engagement, and a removable terminal member held in close contact with said reinforcing member by a screw which engages said rivet.

2. In combination, a carbon block, a U-shaped conducting member fitting over said block, rivets for holding said elements together, a terminal member held in engagement with said conducting member by screws, said screws passing loosely through holes in said block and engaging said rivets, and a conductor in permanent electrical contact with said terminal member.

3. In combination, a carbon block having a reduced portion, a conducting cap having bent down portions engaging said reduced portion, and flush with the surface of the block, rivets passing through said reduced portion and having heads engaging said bent

down portions, holes extending from said cap into said block beyond the rivets, and screws of smaller diameter than said holes passing through said cap, engaging said rivets and clamping a terminal member against said cap.

4. A carbon block having a hole extending through it, another hole perpendicular to said first hole and intersecting it, a cap on 10 said block, a rivet in said first hole having a transverse threaded hole and having headed ends for securing said cap, a screw passing through said cap, occupying said second hole, and engaging said threaded hole 15 in the rivet.

5. A brush for a dynamo electric machine comprising a contact member, a reinforcing cap inclosing one end of said member, means 20 passing through the sides of said cap and the end of said member for securing said parts together, and securing means for an electric terminal passing through said cap and detachably engaging said cap securing means.

6. A brush for a dynamo electric machine 25 comprising a contact member, a reinforcing cap embracing three sides of said member, securing means passing through two sides of said cap and the end of said contact member, an electric terminal, and means for securing 30 said terminal in contact with said cap comprising securing means passing through said

terminal and said cap and engaging said cap securing means.

7. Means for attaching a terminal to a carbon block comprising a reinforcing member embracing opposite sides of said block, securing means passing through said block and the opposite sides of said reinforcing member, an electric terminal, and means for clamping said terminal in position, said 40 means comprising members passing through said terminal and removably engaging said securing means.

8. In a brush for dynamo electric machines, a carbon block, a reinforcing cap embracing one end and two sides of said block, securing means passing through the sides of said cap and said block, a terminal comprising a metallic strip bent on itself, an electric conductor secured in the bend of said terminal, and means for clamping said terminal against the end of said cap, said means comprising fastening members passing through said terminal and cap and removably engaging said securing means.

In witness whereof, I have hereunto subscribed my name in the presence of two witnesses.

WILLIAM L. BLASS.
